TRUCK JOURNAL BOX MOUNTING

Donald S. Barrows, Rochester, N. Y., assignor to
The Symington-Gould Corporation, Depew,
N. Y., a corporation of Maryland

Application July 14, 1944, Serial No. 544,839

30 Claims. (Cl. 105—224)

1

The invention pertains to a railway truck and more particularly to a four wheel type thereof arranged and constructed so as to be suitable for high speeds.

An object of the invention is the provision, in a railway truck, of a pair of laterally spaced side frames having a vertically movable and spring supported bolster structure maintaining the side frames in constant, spaced relation with laterally and vertically movable journal boxes supporting the ends of the side frames.

Another object of the invention is to provide, in a railway truck, laterally and vertically movable journal boxes so as to present an easy riding railway truck and minimize wear of wheel flanges.

A further object of the invention is to provide, in a railway truck, a wheel and axle assembly capable of independent movement transversely of the truck so that lateral thrusts imparted to the assembly during service will be minimized with regard to the side frames, bolster and car body.

These and numerous other objects of the invention will become apparent from the succeeding description considered together with the accompanying drawings which disclose an exemplified form of the invention and wherein:

Figure 1 is a partial vertical sectional and partial side elevational view of a portion of a railway truck embodying the present invention.

Figure 2 is a partial plan and partial horizontal sectional view of the railway truck shown in Figure 1.

Figure 3 is a cross sectional view taken along the lines 3—3 of Figure 1, looking in the direction of the arrows.

Figure 4 is a cross sectional view taken along the lines 4—4 of Figure 1, looking in the direction of the arrows.

Figure 5 is a cross sectional view taken along the lines 5—5 of Figure 1, looking in the direction of the arrows.

Referring now in detail to the drawings wherein there is disclosed by various figures an arrangement and details of a railway truck embodying the present invention, and wherein like numerals designate like parts. The reference character 1 indicates, in a very general manner, a railway truck of the four wheel type. The truck comprises two longitudinally extending, transversely spaced side frames 2, only a portion of one of which is illustrated in the drawings since each side frame is symmetrical about its vertical center and both side frames of the

truck are counterparts of one another. For the last mentioned reason, therefore, only a quarter of the truck is shown in the accompanying drawings, it being clearly understood that all four quarters are identical in every respect, and only where it is deemed necessary for a clear and thorough understanding of the exemplified form of the invention will the hereinafter description deviate from the verbal illustration of the portion of the truck disclosed by the drawings. Each side frame comprises the usual top chord or compression member 3 and lower chord or tension member 4 joined intermediate their ends by longitudinally spaced, vertically extending guide columns 5 to present a bolster or window opening 6 therebetween. Disposed within the window opening and supported by the associated intermediate or horizontal portion 4a of the tension member is a group or nest of resilient means or springs 7 for yieldingly supporting a superimposed bolster 8 having an extremity 9 mounted upon the spring and also positioned within the window opening. The bolster extremity and related columns have a friction device 10 associated therewith so as to snub or control the action of the bolster supporting springs. Forming a part of the friction device is a shoe 11 cast integrally with and outstanding from the bolster extremity to frictionally engage the columns. This arrangement also maintains the side frames in squared relation so as to keep the side frames constantly in a predetermined position transversely of the truck and resist the tendency of one side frame of a pair to lead the other side frame. For a more detailed description and illustration of the bolster-side frame connection reference is hereby made to a copending application for Letters Patent of Glenn F. Couch, Serial Number 383,023, filed March 12, 1941, for Railway truck, and it is deemed sufficient to merely state herein that preferably the side frames and bolster are maintained at all times in squared relation with no horizontal angling movement occurring between the side frames and bolster.

The tension member of the side frame beyond the horizontal intermediate portion at the window opening comprises a transverse web 12 terminating in vertical, transversely spaced flanges 13 all of which extend upwardly and outwardly toward an extremity of the side frame. The compression member, also formed channel-shaped by a horizontal web 14 and transversely spaced flanges 14a, is directed toward an end of the side frame where its flanges merge with the flanges of the tension member to continue in

the same general direction toward the extremity of the side frame in the partial formation of opposing, longitudinally spaced, downwardly and inwardly opening jaws 15 and 15a. The jaw 15 comprises an end wall 16 extending vertically and transversely of the truck and at its upper extremity has merging therewith the web 12 of the tension member to extend therebeyond and terminate in a bifurcated horizontal top wall or web 17 partially defining the upper limits of the jaw 15. The jaw 15a also has an end, transversely directed, vertical wall 16a which is in substantial alignment with the compression member web and terminates in a bifurcated, horizontal top wall or web 17a desirably in the same horizontal plane and merging with the web 17 and also partially defining the upper limits of the jaw 15a. By bifurcating the top wall an aperture 18 is formed for the purpose to be hereinafter explained. Both jaws open toward each other and accordingly each end wall has inner and outer transversely spaced side walls 19 which merge at their upper limits and define a clear opening 20 therebetween.

Extending transversely of the truck between the adjacent extremities of the side frames is a wheel and axle assembly 21 indicated diagrammatically. The journal or free end of each axle outwardly of a related wheel is rotatably associated with a journal box 22 which is disposed within the clear opening 20. A bearing arrangement (not shown) is interposed between the journal box and journal and as indicated, the illustrated journal box is designed for the accommodation of an anti-friction bearing desirably of the type which, while permitting a rotative movement of the wheel and axle assembly relative to the journal box, provides for no lost motion between the axle and journal box when the arrangement is subjected to lateral thrusts. By this arrangement of components, therefore, the wheel, axle and journal box are designed to move in unison transversely of the truck, and while this construction is preferred, it will be clearly understood that the invention need not be necessarily limited to this particular feature. That is to say, it might at times be found desirable to permit lost motion transversely of the truck between the axle and journal box. In any event, it is at present believed more desirable to arrange the journal box and axle so that they will, within certain limits, move transversely of the truck as a unit in response to any laterally directed forces.

Outstanding longitudinally of the truck from the journal box and extending into related downwardly opening jaws are wings 23 each of somewhat box-like formation and comprising a top web 24 directed horizontally from the upper limits or roof 25 of the journal box. Each top web extends to the proximity of a wall 16 or 16a where it terminates by merging with a vertical transversely directed end wall 26 which is of lesser transverse extent than the related jaw end wall so as to permit a transverse movement of the journal box relative to the side frame. The end walls of the side frame jaws and journal box wings are provided with wear plates 27 presenting faces 28 spaced a predetermined distance apart with this distance being determinative of the permissible longitudinal movement of the journal box relative to the side frame. The clearance or distance between the opposing faces 28 is provided so as to permit service movements of the journal box relative to the side frame. As will be noted, the faces 28 form guiding sur-

faces to retain a journal box within a fixed path of travel. The top web and end wall of each wing are reinforced by transversely spaced, vertical, side walls 29 which extend from each side of the journal box to be formed integrally or merge with the transverse limits of the associated top web and end wall. The wing side walls are spaced a lesser distance apart than the jaw side walls and, by reason of this arrangement, the journal box is afforded a certain transverse movement with the extreme limits of such movement defined by the jaw side walls. For the accommodation of structure to be hereinafter described in detail, the wing forming side and end walls terminate a slight distance below a plane intersecting the horizontal axis of the journal box and designated by the diagrammatic line A—A.

Each journal box, as previously indicated, is arranged for movement in a vertical and transverse direction relative to the side frame and, as a precautionary measure in insuring against an accidental separation of the journal box and side frame as well as limit the movement of the journal box in one direction with particular reference to the movement of the journal box downwardly and outwardly of the jaws, there is provided upstanding from the roof of the journal box a strap or eyelet 30 spaced to one side of the vertical center of the journal box. While two eyelets or straps are disclosed, it is believed necessary to employ only one, but for the sake of simplicity in manufacture to avoid making a right hand and left hand journal box, the straps are arranged on each side of the vertical center of the journal box. Each eyelet has an aperture 31 elongated vertically to afford a free vertical service movement of the journal box. Disposed above the journal box and to one side of the vertical center line thereof is a transverse pin, bar or tie means 32 extending through an aperture of one of the eyelets to have its inboard extremity seated in a boss or bearing 33 extending inwardly of the side frame from an inner flange thereof. The outer flange of the side frame in like manner has a boss or bearing 34 projecting inwardly of the side frame for the accommodation and support of the tie means 32. The pin is extended through an opening 35 positioned in the outer flange and in alignment with the bearings. So as to prevent loss or accidental displacement of the bar, a U- or channel-shaped clip 36 is formed integrally with the outer flange and has an overlying apertured portion 37. A retaining bar 38 is inserted beneath the clip to arrest the passage of the tie means from illustrated position. The retaining bar has upstanding legs 39 overlapping the apertured portion of the clip to retain it in position.

Since the box is arranged for vertical movement relative to the side frame a vertically acting spring means 40 is employed to assist in resiliently supporting the side frame from the journal box. The spring means may be of the type hereinafter described or if desired, may be of the snubber type and constructed after the teachings of Letters Patent 2,233,396, granted March 4, 1941, to Emil H. Blattner. The illustrated spring means positioned at the vertical axis of the journal box and, accordingly, extending through the aperture 18, comprises a lower cap 41 bearing upon the roof of the journal box and a vertically spaced upper cap 42 within the compression member and in intimate contact with the web thereof. Interposed between the caps is a compression, coil or helical spring 43

having its opposite ends extending around spuds 44 on each cap to maintain the caps and spring in assembled relation. Each spring cap has an outwardly exposed surface 45 which is preferably cylindrical in configuration and bearing against the journal box roof or compression member web to cradle the resilient means between the side frame and journal box and, so that during a transverse movement of the journal box relative to the side frame, the spring means will rock transversely of the truck to lend itself to service forces. Downstanding from the compression member web and outstanding from the journal box eyelets are spaced retaining means, ears or lugs 46 straddling tongues 47 directed radially of the upper and lower caps and, by reason of this arrangement, the spring means is maintained in a predetermined operable position.

Additional resilient means are associated with the journal box to function as yielding supports for the side frame at this location and, since the side frames are locked together by the bolster to prevent a spreading or approaching movement therebetween, the additional resilient means are so arranged and constructed to facilitate a relatively free journal box transverse movement. As an exemplification of such an arrangement, the upper extremities of the journal box wings adjacent the juncture of the top webs and the inboard side walls thereof are cupped to present longitudinally spaced upwardly facing or opening bearings 48 in each of which nests a bearing shaft, pivot means or pin 49. Accordingly, a bearing shaft is horizontally disposed and associated with each journal box wing to have an axis positioned inwardly of the truck from a vertical longitudinal plane passing through the center of the side frame which, for the sake of clarity, will be hereinafter referred to as the vertical axis of the side frame. This vertical axis of the side frame is indicated in Figure 3 by a diagrammatical line B—B. Depending from each pivot means is a bolt-like swing hanger or suspension means 50 extending vertically from the shaft downwardly through a related wing. Each suspension means is formed by a stem or arm 51 having the upper extremity 52 thereof enlarged and apertured to receive the intersecting pin 49 and for the accommodation of related components projects well below the vertical limits of the journal box. Each swing hanger has an axis indicated by the diagrammatic line C—C intersecting the vertical axis of the side frame and therefore slopes or is inclined transversely of the truck so that from its upper enlarged extremity it is preferably inclined downwardly and outwardly of the truck.

The swing hanger has its lower extremity 53 threaded externally for an appreciable extent and threaded or rotatably associated therewith is a nut-like collar or lower spring seat 54 locked in position by an intersecting cotter key 55 after a predetermined distance between the pivot means and collar has been established. Mounted upon the lower spring seat is a coil or helical spring 56 threaded over the swing hanger stem to be positioned below the overlying wing of the journal box. An upper spring seat 57 intersected by the swing hanger stem and disposed below the related wing, bears upon the helical spring 56 and is arranged to slide along the stem in response to the action of the subjacent supporting spring. Both spring seats are provided with ring like extensions 58 which not only present a

greater bearing area between the seats and swing hanger but also function as centralizing means for the interposed spring. Disposed above the upper spring seat is a horizontal bearing plate or block 59 also intersected by the swing hanger stem and having a central oblong or elongated aperture 60 therein of sufficient extent to afford not only movement of the bearing block vertically or longitudinally of the swing hanger but to prevent interference between the bearing plate and suspension means during a pivotal movement of the latter. To retain the upper spring seat and bearing block in a predetermined fixed relation the upper spring seat has upstanding therefrom spaced lugs 61 which extend into suitable accommodating downwardly opening reliefs or recesses 62 in the bearing block with the lugs and reliefs so arranged as to permit a rocking movement of the swing hanger spring means therebeneath. In order to facilitate the hereinabove mentioned rocking movement which is of course caused by a transverse movement of the journal box relative to the side frame, a boss or bulged portion 63 having a cylindrical, downwardly exposed, convex surface 64 is formed on each bearing block with the latter named surface contacting a crowned, upwardly exposed, convex surface 65 on the upper spring seat. Theoretically at least the contact between the bearing plate and the upper spring seat is represented by a single line directed horizontally and longitudinally of the truck. This line of contact or point of load application to the swing hanger springs is normally at the intersection of the axis of the swing hanger C—C and the vertical axis of the side frame B—B. This load application is below the horizontal axis of the journal A—A to present a stable arrangement and maintains the load at the center line of the side frame or through the vertical axis of the side frame. Again, at least in theory, because the side frames are maintained in service in a fixed position transversely of the truck, the swing hanger revolves or pivots midway between its extremities or about the horizontal line of contact between the bearing plate and upper spring seat or the intersection of the axis C—C and the axis B—B.

So as to transmit the load from the side frame to the swing hanger there is provided a shelf or ledge 66 formed integrally with each jaw side wall adjacent the lower extremity thereof and extending inwardly of the side frame to be mounted or rest upon the bearing block. Each bearing block has an outer downturned flange 67 presenting a plane vertical transversely directed surface 68 which is disposed adjacent to a correspondingly arranged inwardly facing surface 69 carried by a bulged or skirted lower extremity 70 of each jaw end wall. The surfaces 68 and 69 may also, during service, contact one another to maintain the journal box within a predetermined location longitudinally of the truck.

From the above it will be noted that various changes and alterations may be made to the structure of the drawings and description thereof without departing from within the spirit of the invention and scope of the appended claims.

I claim:

1. In a railway truck having a side frame with downwardly opening jaws at one end thereof and a vertically and transversely movable journal box between said jaws, the combination of, means upstanding from said journal box, tie means associated with said side frame and intersecting

said upstanding means, means outstanding from said journal box and extending into said jaws, hanger means pivotally carried by said outstanding means, a bearing plate associated with each of said hanger means, means within said jaws resting upon said bearing plate, and spring means between each bearing plate and one end of each hanger means, said hanger means being arranged to pivot transversely of said truck about a point between said bearing plate and spring means.

2. In a railway truck having a side frame with downwardly opening jaws at one end thereof and a vertically and transversely movable journal box between said jaws, the combination of, guide means outstanding from said journal box and extending into and arranged to be contacted by said jaws, hanger means pivotally carried by said guide means, bearing means associated with each of said hanger means, means within said jaws adjacent the lower extremities thereof and resting upon said bearing means, and spring means between each bearing means and one end of each of said hanger means.

3. In a railway truck having a side frame with downwardly opening jaws at one end thereof and a vertically and transversely movable journal box between said jaws, the combination of, means outstanding from said journal box and extending into said jaws, transversely disposed surfaces carried by said outstanding means associated with correspondingly disposed surfaces carried by said jaws for guiding said journal box transversely of said side frame, hanger means pivotally carried by said outstanding means, horizontal means movable longitudinally of said hanger means and disposed intermediate the ends of said hanger means, means extending inwardly of and associated with said side frame and bearing upon said horizontal means, and spring means carried by said hanger means and supporting said horizontal means.

4. In a railway truck having a side frame with downwardly opening jaws at one end thereof and a vertically movable journal box between said jaws, the combination of, means outstanding from said journal box and extending into said jaws, pivot means carried by said outstanding means and having an axis disposed inwardly of said truck from the vertical axis of said side frame, hanger means carried by said pivot means, means movable longitudinally of said hanger means and disposed intermediate the ends of said hanger means, said movable means carrying said side frame, a center line of said hanger means intersecting said vertical axis adjacent a center of said movable means, and spring means carried by said hanger means and supporting said movable means.

5. In a railway truck having a side frame with downwardly opening jaws at one end thereof and a vertically and transversely movable journal box between said jaws, the combination of, a transversely rockable spring means interposed between a roof of said journal box and a compression member of said side frame, means outstanding from said journal box and arranged to guide said journal box during said transverse movement, swing hangers within said jaws and pivotally mounted on said outstanding means, means movable longitudinally of said swing hangers and disposed within said jaws, means extending inwardly of said jaws above said movable means and bearing upon said movable means, and spring

means carried by said swing hangers and supporting said movable means.

6. In a railway truck having a side frame with downwardly opening jaws at one end thereof and a vertically and transversely movable journal box between said jaws, the combination of, a transversely rockable spring means interposed between a roof of said journal box and a compression member of said side frame, means outstanding from said journal box, swing hangers within said jaws and outstanding means and pivotally mounted on said outstanding means, means movable longitudinally of said swing hangers and disposed within said jaws, means extending inwardly of said jaws above said movable means and bearing upon said movable means, spring means carried by said swing hangers and supporting said movable means, and rocker means on said movable means bearing upon said spring means.

7. In a railway truck having a side frame with downwardly opening jaws at one end thereof and a vertically and transversely movable journal box between said jaws, the combination of, a transversely rockable spring means interposed between a roof of said journal box and a compression member of said side frame, means outstanding from said journal box, inclined swing hangers within said jaws and outstanding means and pivotally mounted on said outstanding means, means movable longitudinally of said swing hangers and disposed within said jaws, means extending inwardly of said jaws and bearing upon said movable means, and spring means carried by said swing hangers and supporting said movable means, the center line of said swing hangers intersecting a vertical axis of said side frame adjacent a vertical center of said movable means.

8. In a railway truck having a side frame with downwardly opening jaws at one end thereof and a vertically and transversely movable journal box between said jaws, the combination of, hanger means movably mounted on said journal box, spring means carried by said hanger means, and means above and rockably associated with said spring means and being interposed between said spring means and side frame for supporting said side frame, a contact between said last named means and spring means remaining substantially constant transversely of said truck and relative to said side frame during a transverse movement of said journal box.

9. In a railway truck having a side frame with downwardly opening jaws at one end thereof and a vertically and transversely movable journal box between said jaws, the combination of, hanger means normally disposed at an angle to said side frame, means connecting said hanger means and journal box, spring means spaced from said connecting means and carried by said hanger means, and means interposed between said spring means and side frame for the support of the latter, said last named means functioning as a pivotal support above said spring

means, all of said means being arranged and constructed so as to permit said hanger means to move in a direction transversely of said truck about a point between said spring means and last named means.

10. In a railway truck having a side frame with downwardly opening jaws at one end thereof and a vertically and transversely movable journal box between said jaws, the combination of, hanger means pivotally associated with said journal box inwardly from a vertical axis of said

side frame, said hanger means being inclined transversely of said truck with respect to said side frame, spring means carried by said hanger means, and means interposed between said spring means and side frame for supporting the latter; said hanger means being arranged to pivot about a point adjacent an intersection of a center line of said hanger means and a vertical axis of said side frame.

11. In a railway truck having a side frame with downwardly opening jaws at an end thereof and a transversely and vertically movable journal box disposed between said jaws, the combination of, inclined hanger means pivotally associated with said journal box, spring means sleeved over and carried by said hanger means, and rocker means sleeved over and carried above and by said spring means; said rocker means directly supporting said side frame.

12. In a railway truck having a side frame with downwardly opening jaws at an end thereof and a transversely and vertically movable journal box disposed between said jaws, the combination of, inclined hanger means pivotally associated with said journal box, spring means including a crowned spring plate sleeved over and carried by said hanger means, bearing means sleeved over said hanger means and resting upon said crowned spring plate, and means associated with said bearing means for supporting said side frame.

13. In a railway truck having a side frame with downwardly opening jaws at an end thereof and a transversely and vertically movable journal box disposed between said jaws, the combination of, hanger means pivotally associated with said journal box, spring means sleeved over and carried by said hanger means, bearing means sleeved over said hanger means and carried by said spring means, and means mounted upon said bearing means for supporting said side frame; said bearing means being rockably mounted on said spring means.

14. In a railway truck having side frames maintained in constant transverse, spaced relation by a connecting bolster and the side frames comprising spaced jaws with transversely and vertically movable journal boxes therebetween, the combination of, wings extending from each journal box into associated jaws, hanger means pivotally connected to and extending through said wings, spring means carried by said hanger means adjacent the lower extremities thereof, rocker means supported by said spring means, and means within said jaws above said rocker means bearing upon said rocker means for supporting said side frames.

15. In a railway truck having side frames maintained in constant transverse, spaced relation by a connecting bolster and the side frames comprising spaced jaws with transversely and vertically movable journal boxes therebetween, the combination of, wings extending from each journal box into associated jaws, hanger means pivotally connected to said wings, said hanger means being inclined transversely of said truck with respect to said side frames, surfaces carried by said wings outwardly of said hanger means adapted to contact correspondingly disposed surfaces on said side frames to limit movement of said journal boxes longitudinally of said truck, spring means sleeved over said hanger means, rocker means sleeved over said hanger means and supported by said spring means, and means

within said jaws bearing upon said rocker means for supporting said side frames.

16. In a railway truck having side frames maintained in constant spaced relation by a vertically movable connecting bolster, said side frames comprising spaced jaws with transversely and vertically movable journal boxes therebetween, the combination of, spring means arranged to pivot transversely of said truck and being interposed between roofs of said journal boxes and portions of said side frames thereabove, wings extending from each journal box into associated jaws, hanger means pivotally carried by said wings, spring means carried by said hanger means, rocker means supported by said spring means, and means within said jaws bearing upon said rocker means for supporting said side frames; each of said hanger means being arranged to pivot about a point adjacent an intersection of a center line of said hanger means and vertical axis of an associated side frame.

17. In a railway truck having a side frame with downwardly opening jaws at one end thereof and a vertical and transversely movable journal box positioned between said jaws, the combination of, wings extending from said journal box into said jaws, pivot means carried by said wings, swing hangers extending through said wings and carried by said pivot means, spring means below said wings and supported by said swing hangers, bearing blocks below said wings and bearing upon said spring means, and means directed inwardly of said side frame from said jaws and supported by said bearing blocks.

18. In a railway truck having a side frame with downwardly opening jaws at one end thereof, and a vertical and transversely movable journal box positioned between said jaws, the combination of, integral wings extending from said journal box into said jaws, pivot means carried by said wings, swing hangers extending through said wings and carried by said pivot means, spring means below said wings and supported by said swing hangers, bearing blocks below said wings and bearing upon said spring means, and means directed inwardly of said side frame from said jaws and supported by said bearing blocks: said bearing blocks being disposed below the horizontal axis of said journal box.

19. In a journal box arranged to move vertically with respect to a side frame, the combination of, wings outstanding from said journal box, each of said wings comprising a top horizontal web and laterally spaced vertical flanges joining each of said top webs and journal box, vertical end walls extending between said side walls, a socket adjacent the upper extremity of each wing for the accommodation of hanger pivot means, and means upstanding from said journal box for the accommodation of means limiting the permissible journal box movement.

20. In a side frame formed by a tension and compression member merging adjacent an extremity of said side frame to present opposing jaws forming an opening for the accommodation of a transversely movable journal box, the combination of, each jaw comprising an end wall merging with transversely spaced side walls extending towards said opening, and shelf means directed inwardly of said jaws from each side wall for transmitting a load from said side frame to subjacent spring means, said shelf means terminating short of a vertical central plane of said side

frame for the accommodation of swing hanger means.

21. In a journal box arranged to move vertically with respect to a side frame, the combination of, wings outstanding from said journal box, each of said wings comprising a top horizontal web and laterally spaced vertical flanges joining each of said top webs and journal box, vertical end walls extending between said side walls for guiding said journal box along a vertical path and a socket adjacent an upper extremity of each wing for the accommodation of hanger means.

22. In a railway truck having a side frame with downwardly opening jaws at an end thereof and a transversely movable journal box between said jaws, the combination of, oppositely directed extensions on side walls of said journal box projecting into said jaws, one part of each extension spaced from said journal box arranged to be contacted by said jaws during a transverse movement of said journal box and another part of each extension joining said first named part to said journal box arranged to contact said jaws for limiting said transverse movement, and hanger means carried by said extensions for the support of said side frame.

23. In a railway truck having a side frame with downwardly opening jaws at an end thereof and a transversely movable journal box between said jaws, the combination of, oppositely directed extensions on side walls of said journal box projecting into said jaws, one part of each extension spaced from said journal box arranged to be contacted by said jaws during a transverse movement of said journal box and another part of each extension connecting said first named part and journal box arranged to contact said jaws for limiting said transverse movement, hanger means carried by said extensions and disposed between said journal box and first named parts for the support of said side frame, and rocking means interposed between said hanger means and side frame for facilitating said transverse movement.

24. In a railway truck having a side frame with downwardly opening jaws at an end thereof and a transversely movable journal box between said jaws, the combination of, hanger means movably associated with said journal box inwardly from a vertical axis of said side frame, said hanger means being inclined transversely of said truck with respect to said side frame, means interposed between said hanger means and side frame for supporting the latter, said hanger means being arranged to pivot intermediate its ends about a point adjacent an intersection of a center line of said hanger means and a vertical axis of said side frame and yieldable means between said second named means and a lower end of said hanger means.

25. In a railway truck having a side frame with downwardly opening jaws at an end thereof and a transversely movable journal box between said jaws, the combination of, guiding wing means outstanding from side walls of said journal box and extending into said jaws, hanger means carried by said wing means inwardly from a vertical axis of said side frame, said hanger means being inclined through said wing means transversely of said truck with respect to said side frame, means carried by said hanger means intermediate the ends thereof for supporting said side frame; an axis of said hanger means intermediate the ends thereof intersecting said verti-

cal axis with this point of intersection remaining constant transversely of said truck and relative to said side frame during said transverse movement of said journal box.

26. In a railway truck having a side frame with downwardly opening jaws at an end thereof and a vertically and transversely movable journal box between said jaws, the combination of, wing means outstanding from side walls of said journal box and extending into said jaws, outer limits of said wings being guidingly associated with said jaws and inner parts of said wings arranged to contact said jaws for limiting said transverse movement, hanger means carried by bridges between said outer limits and inner parts of said wing means inwardly from a vertical axis of said side frame, said hanger means being inclined transversely of said truck with respect to said side frame, resilient means carried by said hanger means for yieldingly supporting said side frame; an axis of said hanger means intersecting said vertical axis with this point of intersection remaining constant transversely of said truck and relative to said side frame during said transverse movement of said journal box.

27. In a railway truck having a side frame with downwardly opening jaws at an end thereof and a vertically and transversely movable journal box between said jaws, the combination of, rectangular wings outstanding from said journal box and extending into said jaws for guidingly contacting said jaws during said vertical movement and contacting said jaws for limiting said transverse movement, swing hangers carried by said wings, spring means carried by said swing hangers, spring caps mounted upon said spring means, crowned surfaces on said spring caps, bearing plates mounted upon said spring caps, crowned surfaces on said bearing plates contacting said spring cap crowned surfaces, and means extending inwardly of said side frame bearing upon said bearing plates.

28. In a railway truck having a side frame with downwardly opening jaws at an end thereof and a vertically and transversely movable journal box between said jaws, the combination of, rectangular wings outstanding from said journal box and extending into said jaws for guidingly contacting said jaws during said vertical movement and contacting said jaws for limiting said transverse movement, swing hangers carried by and extending through said wings, spring means carried by said swing hangers below said wings, spring caps mounted upon said spring means below said wings, crowned surfaces on said spring caps, bearing plates mounted upon said spring caps, crowned surfaces on said bearing plates contacting said spring cap crowned surfaces, and means formed integrally with said jaws and bearing upon said bearing plates.

29. In a railway truck having a side frame with downwardly opening jaws at an end thereof and a vertically and transversely movable journal box between said jaws, the combination of, rectangular wings outstanding from said journal box and extending into said jaws for guidingly contacting said jaws during said vertical movement and contacting said jaws for limiting said transverse movement, swing hangers carried by said wings, spring means carried by said swing hangers, spring caps mounted upon said spring means, crowned surfaces on said spring caps, bearing plates mounted upon said spring caps, crowned surfaces on said bearing plates contacting said

13

spring cap crowned surfaces, and means extending inwardly of said side frame bearing upon said bearing plates; said swing hangers being angularly disposed relative to a vertical axis of said side frame and a point of intersection of said vertical axis and an axis of said swing hanger coinciding with the contact between the crowned surfaces of said bearing plates and spring caps.

30. In a railway truck having a side frame with 10 downwardly opening jaws at an end thereof and a vertically and transversely movable journal box between said jaws, the combination of, wings outstanding from side walls of said journal box and extending into said jaws, inclined hangers supported by said jaws, spring means surrounding 15 said hangers and supported thereby below said wings, spring plates having upwardly facing cylindrical surfaces mounted upon said spring means, bearing plates mounted upon and having 20

14

downwardly facing cylindrical surfaces contacting said upwardly facing cylindrical surfaces of said spring plates, and ledges carried by said jaws and mounted upon said bearing plates.
